[57] CLAIM

The ornamental design for a shelving device, as shown and described.

DESCRIPTION

FIG. 1 shows an exploded perspective view of both components of the shelving device;

FIG. 2 shows a top view of both components of the shelving device;

FIG. 3 shows a bottom view of both components of the shelving device.

FIG. 4 shows a front view of both components of the shelving device;

FIG. 5 shows a back view of both components of the shelving device;

FIG. 6 shows a right side view of both components of the shelving device, the left side being a mirror image;

FIG. 7 shows a top view of the top member of the shelving device, shown separately for clarity of illustration;

FIG. 8 shows a bottom view of the top member of FIG. 7;

FIG. 9 shows a front view of the top member of FIG. 7;

FIG. 10 shows a back view of the top member of FIG. 7;

FIG. 11 shows a right side view of the top member of FIG. 7;

FIG. 12 is a top view of the lower member of the shelving device, shown separately for clarity of illustration;

FIG. 13 shows a bottom view of the lower member of FIG. 12;

FIG. 14 shows a side view of FIG. 12, the opposite side being a mirror image;

FIG. 15 shows a front view of FIG. 12;

FIG. 16 shows a back view of the lower member of FIG. 12;

FIG. 17 is an enlarged fragmentary perspective view of the right front corner of FIG. 8; and,

FIG. 18 is an enlarged fragmentary perspective view of the right rear corner of FIG. 8.
